PACKING STRUCTURE FOR DRY CELLS

Paul F. Boeye, St. Paul, Minn., assignor to Wal-dorf Paper Products Company, St. Paul, Minn., a corporation of Minnesota

Application May 31, 1930. Serial No. 458,633

9 Claims. (Cl. 206—46)

My invention relates to packing structures and particularly to packing structures adapted to be used for packing dry cells for shipment.

An object of the invention resides in providing a structure including a box in which the dry cell may be packed, said structure preventing the dry cells from being injured during shipment thereof.

Another object of the invention resides in providing the box in which the dry cells are disposed with a bottom on which the dry cells may rest and a top spaced from the upper ends of the dry cells, and in further arranging the dry cells in a plurality of rows within said box, and in disposing partitions between the rows of dry cells and other partitions between the individual cells of each row.

A feature of the invention resides in providing spacers adapted to be disposed between the upper ends of the dry cells and the top of the box for holding the dry cells in place within the box and for preventing the binding posts of the dry cells from contacting with the top of the box.

An object of the invention resides in constructing said spacers in the form of strips with portions lying between the respective binding posts of each dry cell to assist in preventing the binding posts of adjacent dry cells from contacting with one another.

Another object of the invention resides in providing members operating in conjunction with said spacers and extending at right angles thereto, said members having portions lying between the binding posts of the corresponding dry cells of adjacent rows to further assist in preventing the binding posts of adjacent dry cells from contacting with one another.

A still further object of the invention resides in forming portions of the surfaces of said partitions in proximity to the upper and lower ends of said dry cells and opposite the adjacent portions thereof discontinuous to cause said dry cells to clear the partitions and one another so as to prevent injury to the extreme ends of the dry cells.

A feature of the invention resides in forming the portions for clearing the upper and lower ends of the dry cells by cutting away parts of the partitions.

An object of the invention resides in constructing the partitions of sufficient thickness to prevent the protruding parts of the dry cells disposed within the cut away portions of said partitions from contacting with one another.

Other objects of the invention reside in the novel combination and arrangement of parts and

in the details of construction hereinafter illustrated and/or described.

Dry cells are usually constructed from a zinc shell closed at the top through a suitable sealing wax cap and encased in a suitable paste board case having a bottom overlapping the sides of the case. Such dry cells are ordinarily provided with binding posts protruding outwardly beyond the dry cell proper, the negative post being attached to the zinc shell. In the shipment of such dry cells the wax, which is extremely fragile, readily becomes broken through the engagement of adjoining dry cells with one another near the upper ends thereof or with other solid objects and through similar engagement of the negative binding posts with one another or with other objects. In addition such dry cells frequently become injured at the locality of the overlapping portions of the bottom and side wall structure of the case and the binding posts often become loosened and occasionally broken. With my invention, such injury to the cells is prevented and the dry cells are packed in such a manner that the same are practically immovable within the shipping container in which they are disposed so that rough handling and misuse of the container cannot cause the dry cells to contact with one another at the fragile portions thereof, thereby preventing injury to the cells during the shipment thereof.

In conjunction with my invention, I employ a container which may be of any desired type or construction. For the purpose of illustration I have shown in all of the forms of the invention an ordinary pasteboard box indicated in its entirety at 30 which comprises sides 31 and 32 and ends 33 and 34. This box may be constructed with a bottom indicated in its entirety at 35 which consists of a number of flaps 36 bent from the lower edges of the sides 31 and 32 and the ends 33 and 34 of the box. In a similar manner, the top indicated in its entirety at 37 (Fig. 2) is constructed from a number of flaps 38 which are bent from the upper edges of the sides 31 and 32 and the ends 33 and 34 of the box and which are adapted to be secured to one another as by gluing or in any other suitable manner such as is now well known in the art. The particular construction of the box 30 forming no feature of the invention, it can readily be comprehended that any suitable construction may be employed and the box built from any suitable material.

As previously stated, the invention is primarily for the purpose of packing dry cells. In order to more clearly illustrate the application of the invention a number of dry cells 29 have been illustrated in the various forms of the invention, which dry cells are identical in construction. Each of these dry cells comprise a cylindrical case 39 in which the dry cell proper is contained, which case is constructed with a bottom 40 having a rim-like portion or band 41 integrally connected therewith. This rim-like portion overlaps the lower end of the case proper and is secured thereto as by gluing or otherwise. This rim-like portion or band 41 encircles the entire case along the lower end thereof and causes this part of the case to protrude outward-

ly beyond the remainder of the case. The dry cell proper is constructed in the usual manner with a zinc case which is closed at the upper end thereof with a wax cap 42. The dry cell includes a negative binding post 43 and a positive binding post 44 which extend upwardly from the cap 42. The positive binding post 44 is usually disposed centrally with respect to the dry cell while the negative binding post 43 is attached to the zinc shell of the dry cell and extends appreciably outwardly beyond the exterior surface of the case 39 when the dry cell is mounted within the case. In the form of dry cell shown, the case 39 is open at the top to expose the wax cap 42 though in some types of dry cells, said case may be closed. The invention operates equally as well with either type of dry cell and holds the dry cell supported so as to prevent injury thereto.

In the form of the invention shown in Fig. 1 I employ a number of partitions 45 and 46 illustrated in Figs. 4 and 5 which are constructed of any suitable material such as cardboard or the like. The partitions 45 are constructed with longitudinal slits 47 extending from the lower edges thereof and upwardly, while the partitions 46 are similarly constructed with slits 48 extending from the upper edges thereof and downwardly. By means of these slits the various partitions may be interconnected with one another to form spaced compartments 58 as best shown in Figs. 105 1 and 3 for the reception of the various dry cells. The box proper and these partitions are so proportioned that the cases 39 of the various dry cells fit snugly between said partitions and the sides and ends of the box when inserted into the same.

For the purpose of clearing the rim or band 41 on the case 39 of the various dry cells, the extreme lower edges 49 of the partitions 45 and 46 are formed with a number of slots 50 which are of a height greater than the height of said bands and which are located in proximity to the tangent portions of the dry cells. These slots form pockets into which said bands or rims 41 of the dry cells may extend. In this manner, the lower portions of the dry cells are free from the partitions while the intermediate portions thereof are firmly in contact with said partitions. The partitions 45 are constructed of a length equal to the distance between the top 37 and the bottom 35 of the box 30 so as to hold said partitions from movement when the box is closed. As will be noted in Fig. 1 the partitions 46 are considerably shorter than the partitions 45. The partitions 46 are held in place within the box through the slits 47 and 48 which are so disposed as to permit downward movement only of the partitions 46 with respect to the partitions 45 thereby precluding the movement of any of the partitions when the box is closed.

For the purpose of preventing injury to the wax caps 42 of the dry cells, the upper ends of the partitions 45 are formed with slots 60 which extend downwardly from the edges of said partitions and to a distance somewhat below the extreme upper edges 51 of the various dry cells. These slots correspond to the slots 50 and are so disposed as to lie opposite the portions of the dry cells contacting with the various partitions so that the extreme upper ends of the dry cells are free from said partitions and from one another. These slots are preferably of such a depth that the lower edges 52 thereof come below the wax caps 42. By means of this construction the contacting of the upper portions of 150

the dry cells is entirely precluded so that injury to the wax cap 42 of the dry cells through contact with adjacent dry cells is prevented. The partitions 46 are of such a height that the same reach up to the lower edges 52 of the slots 60 so that the upper edges of the dry cells are free on all sides thereof and injury thereto prevented.

In order to hold the dry cells 29 from longitudinal movement within the box 30 a number of spacer strips 53 are employed which are shown detached from the packing structure in Fig. 6. These spacer strips are preferably constructed from corrugated board and are bent in the shape of a U to form side members 54 and 55 and a connecting member 56. The spacer strips 53 are of such a width as to be snugly received within the slots 60 of the partitions 45, and the side members 54 thereof are of such a height that when the same rest upon the caps 42 of the various dry cells the connecting portion 56 of said members snugly contacts with the under surface of the top 37 of the box proper. The distance between the side portions 54 and 55 of the spacer strips 53 is such that the same forms a space 57 of suitable dimensions to comfortably receive the positive binding post 44 of the various dry cells. This leaves one of the side members 54 and 55 disposed between respective binding posts of each of the dry cells which checks the rotation of the dry cells in one direction thereby preventing the binding posts of adjacent dry cells from contacting with one another, when the dry cell is rotated in such direction.

In the use of this form of the invention, the partitions are assembled and placed within the interior of the box 30 through the open upper end thereof. The dry cells are then placed one by one within the various compartments 58 formed between the partitions 45 and 46. This is readily accomplished through the springing of said partitions and the walls of the box and particularly before the cover of the box has been closed. After all of the dry cells have been placed within the various compartments, said dry cells are turned so that the negative binding posts thereof lie in the corners of said compartments in which said binding posts are as far away from one another as possible. The spacer strips 53 are next inserted into the slots 60 and the cover 37 closed by folding the various flaps 38 upon one another and gluing or otherwise securing the same together. The dry cells are now lodged within the interior of the box 30 in such a manner that the cases 39 of said dry cells contact with one another throughout their extent excepting at the extreme upper and lower ends thereof which are free from one another and from the partitions of the device. At the same time the spacer strips 53 hold the dry cells from longitudinal movement and protect the binding posts from contacting with the top 37 of the box and also serve to prevent the dry cell from rotating to bring the negative binding post in contact.

The form of the invention shown in Figs. 7, 8 and 9 differs only from that shown in Fig. 1 in the use of a slightly modified type of spacer. This spacer is illustrated in Fig. 12 and is indicated in its entirety at 61. The spacer 61 is identical with the spacer strip 53 excepting that the side portion 54 thereof is constructed with a number of tabs 62 extending outwardly therefrom. These tabs are spaced apart a distance equal to the width of the compartments 58 and

are adapted to extend medially over the various dry cells and to operate in conjunction with the sides 54 and 55 of said spacers to preclude the rotation of the dry cell so as to prevent the negative binding posts from coming into any position whereby the same will contact with one another or with any other portion of the packing device whereby injury to the dry cell might result. For the purpose of supporting the tabs 62, a partition 63 is employed which is used in place of the partition 46 and which is constructed identically the same as the partition 45 with slots 64 corresponding to the slots 60. This partition however is formed with the slits 68 the same as the slits in the partition 46 so that the same may be assembled with the partitions 45 to support the dry cells as previously brought out. When the spacers 61 are laid in the slots 60 the tabs 62 thereof extend into the slots 64 where the same are held from movement and the dry cells rigidly and firmly supported in proper position.

In Fig. 13, I have shown a still different form of spacer. With this form of the invention exactly the same type of partitions are employed as illustrated in Figs. 10 and 11, these partitions being designated by the reference numerals 45 and 63. The spacers used with this modification of the invention consist of small strips of cardboard or the like which are indicated at 65 and 66. The strips 65 are constructed with slits 67 extending upwardly from the lower edges thereof and the strips 66 are constructed with similar slits 68 extending downwardly from the upper edges thereof. These strips are adapted to be interconnected to form a cellular structure similar to the partitions 45 and 63. It will be noted that the slits 67 and 68 are not centrally disposed with respect to said strips. The slits are on the contrary so arranged that when the strips are assembled, the same lie adjacent the edges of the slots 60 and 64 of the partitions 45 and 63. This causes the said strips to clear the positive terminals 44 of the various dry cells and to form small compartments 69 between said strips and said partitions to receive the negative binding posts of the dry cells. By means of this construction the dry cells are prevented from rotating so that the negative binding post cannot come in contact with one another thereby preventing injury to the dry cells.

In Figs. 20 to 25 a still different form of the invention is illustrated. This form of the invention is substantially the same as that illustrated in Fig. 13 excepting for the difference in construction of the spacers employed. However, in this form of the invention, the box which is employed and which is indicated at 70 is of slightly less height than the box 30 shown in Fig. 1 and the partitions 71 and 72 employed therewith are of slightly less height than the partitions 45 and 63 of the other forms of the invention. With the exception of the difference in height the construction of both the box 70 and the partitions 71 and 72 is exactly the same as the box 30 and the partitions 45 and 63. In this form of the invention, a spacer strip such as shown at 73 is employed which is constructed of corrugated board or some other suitable board having an appreciable thickness. This strip is of a width somewhat greater than the diameter of the binding post of the dry cell and is constructed with a number of holes 74 disposed at suitable intervals to receive the positive binding post 44 of the dry cells. In the use of this form of the invention the strips 73 are disposed within the slots 60 and 64.

of the various partitions 71 and 72 so that the binding posts are received within the opening 74 in said device. It will be noted in Fig. 21 that two sets of strips are employed which are arranged at right angles to one another so that the same form in conjunction with the upper ends of the partitions 71 and 72 compartments similar to the compartments 69 of the form of the invention shown in Fig. 13, whereby the dry cells are deprived of rotation and the negative binding posts 43 fully protected. The thickness of the strips 73 is somewhat greater than one-half the height of the binding post above the upper surfaces of the dry cells so that the upper ends of the said binding posts are clear of the top 37 of box 70. In this manner the dry cells are held in identically the same relation with respect to the various parts of the box as in the form of the invention shown in Fig. 3.

In Figs. 26 to 31, I have shown a form of the invention in which the clearance provided at the delicate parts of the dry cells may be formed without the use of slots extending completely through the partitions. In this form of the invention, a box 75 is employed which is identical with the box 30 excepting that the same may be slightly larger in dimensions due to the fact that partitions of a slightly greater thickness are employed. Otherwise the said box is identically the same as that employed in the various other forms of the invention and particularly the box shown in Fig. 1. The partitions utilized in this form of the invention are shown in detail in Figs. 28 and 29 and are indicated at 76 and 77. These partitions are constructed of corrugated board or some other readily compressible material of like nature. The partitions 76 and 77 extend the full height of the box and are formed with slits 78 and 79 corresponding with the slits 47 and 48 of the other forms of the invention whereby said partitions may be interconnected in identically the same manner to form compartments in which the various dry cells may be disposed. The extreme upper ends 80 and 81 of the partitions 76 and 77 and the lower ends 82 and 83 thereof are compressed or flattened to a thickness less than the major portion of said partitions as best shown in Fig. 31. This may be accomplished by rolling the end portions of said partitions or in any other suitable manner. By means of this construction a space 84 is formed on either side of the surface of said partitions which is adapted to receive the bands or rims 41 of the various dry cells or the upper portions of said dry cells so as to prevent the same from contacting with one another as in the other form of the invention. The compressed portions of the partitions 76 and 77 serve the same purpose as the slots 50 and 60 of the other forms of the invention.

In conjunction with the structure shown in Figs. 26 and 27, I employ a spacer illustrated in detail in Fig. 30. This spacer is indicated in its entirety at 85 and comprises a strip of sheet material which is bent along three parallel lines 86, 87 and 88 to form a rectangle best shown in Fig. 30. This rectangle is adapted to be inserted into the upper portions of the various compartments formed between the partitions 76 and 77 and the walls of the box 75 and engages the upper ends of the dry cells and the under side of the box in identically the same manner as the strips 65 and 66 used in the form of the invention shown in Fig. 13. The length of the portions of said strip 85 between the folds 86, 87 and 88 thereof is somewhat greater than the width of

the compartments between the partitions 76 and 77 so that the said strips become bowed as indicated at 89 when inserted into said compartments causing the intervening portions of said strips to extend across the upper end of the dry cells at 80 positions inwardly from the outer edges of the cases 39 of said dry cells. The spacer 85 is so disposed and the negative binding post of the dry cell is so arranged in respect to said spacer that the same lies between the two ends 90 and 91 of the spacer so that said binding post is held from movement and rotation of the dry cell prevented thereby precluding the possibility of injuring the dry cell through the contacting of the negative posts of adjacent dry cells.

The method of using the various forms of the invention are all the same. The various partitions are assembled and inserted into the box and the dry cells disposed within the various compartments with the negative posts in the corners of the compartments. The respective spacers are then placed in the proper positions above the dry cells and the cover of the box sealed.

The advantages of my invention are manifest. The dry cells are firmly and immovably held within the box so that the same cannot strike or contact with one another at easily fragile portions to cause injury thereto. The dry cells contact with the partitions along portions of said dry cells capable of withstanding considerable 105 shock and are free from said partitions and from one another at the more delicate portions thereof. The dry cells are held from movement longitudinally with respect to the box through the spacer strips which at the same time prevent the 110 binding posts of the dry cells from contacting with the cover of the box. The dry cells are held from rotation so that the negative binding posts cannot contact with one another and injure the dry cells, and the portion of the dry cell adjacent 115 the wax cap thereon is entirely free from contact with any portion of the partitions or from contact with one another so that injury to this portion of the dry cell is entirely precluded. The device can be constructed by ordinary means and 120 at a nominal expense.

Changes in the specific form of my invention as herein described may be made within the scope of what is claimed without departing from the spirit of my invention.

Having described my invention what I claim as new and desire to protect by Letters Patent is:

1. A packing structure for a plurality of dry cells adapted to be arranged in a row comprising a box for the reception of the dry cells having a bottom on which the dry cells may rest and a top spaced from the upper ends of the dry cells, a plurality of partitions separating the cells in the row, and an elongated spacer disposed between the upper ends of the dry cells and the top of said box, said spacer having a portion extending between the respective binding posts of each of said dry cells.

2. A packing structure for a plurality of dry cells adapted to be arranged in a row comprising a box for the reception of the dry cells having a bottom on which the dry cells may rest and a top spaced from the upper ends of the dry cells, a plurality of partitions separating the cells in the row, and an elongated spacer disposed between the upper ends of the dry cells and the top of said box, said spacer having a portion extending between the respective binding posts of each of said dry cells, and means extending at right 150

angles to said spacer and forming in conjunction with said spacer confined spaces for the reception of one of the binding posts of each of said dry cells, said spaces preventing the binding posts of 5 adjacent dry cells from contacting with one another.

3. A packing structure for a plurality of dry cells arranged in parallel rows comprising a box for the reception of said dry cells having a bottom on which the dry cells may rest and a top spaced from the upper portion of the dry cells, partitions within said box disposed between the rows of dry cells, other partitions within the box disposed between the individual cells of each row, 10 15 a spacer strip extending along said rows and disposed between the upper portions of said dry cells and the top of said box, said spacer strip having portions lying between the respective binding posts of each dry cell of a row, and means 20 extending at right angles to said spacer strip, said means having portions lying between the binding posts of adjacently lying dry cells of succeeding rows.

4. A packing structure for a plurality of dry cells adapted to be arranged in a row comprising a box for the reception of the dry cells having a bottom on which the dry cells may rest and a top spaced from the upper ends of the dry cells, a plurality of partitions separating the cells in the 25 30 row, and an elongated spacer disposed between the upper ends of the dry cells and the top of said box, said spacer having a portion extending between the respective binding posts of each of said dry cells, said partitions extending from said 35 bottom of said box to the top and having notches therein for the reception of said spacer strip.

5. A packing structure for a plurality of dry cells adapted to be arranged in a row comprising a box for the reception of the dry cells having a bottom on which the dry cells may rest and a top spaced from the upper ends of the dry cells, a plurality of partitions separating the cells in the 40 45 row, and an elongated spacer disposed between the upper ends of the dry cells and the top of said box, said spacer having a portion extending between the respective binding posts of each of said dry cells, and of a width less than that of said cells, said partitions extending from said

bottom of said box to the top, and having notches therein for the reception of said spacer strip, said notches being of a width substantially equal to the width of the spacer strip to retain the spacer strip in position to separate the binding 80 posts.

6. A packing structure for cylindrical dry cells formed with a wax cap, said structure comprising a box for the reception of the dry cells, a partition within the box disposed between the dry 85 cells and contacting with the tangential surfaces thereof, said partition being free from the dry cells at the localities of the wax caps thereof, and means superimposing said partition and disposed between the binding posts of the dry cells 90 for protecting the dry cells.

7. A packing structure for cylindrical dry cells formed with a wax cap, said structure comprising a box for the reception of the dry cells, a partition within the box disposed between the dry 95 cells and contacting with the tangential surfaces thereof, said partition being formed with slots extending below the wax caps of the dry cells and terminating at lateral localities just clearing the tangent surfaces of the dry cells at the wax caps. 100

8. A packing structure for cylindrical dry cells formed with a wax cap and binding posts at the upper ends and with a band encircling the lower end, said structure comprising a box for the reception of the dry cells, a partition in the box, 105 said partition being formed with slots in the top and bottom, the lower slot extending up above the band of the dry cell and the upper slot being of a length greater than the lower slot and extending below the wax cap of the dry cell. 110

9. A packing structure for cylindrical dry cells having binding posts at the upper ends thereof, said structure comprising a box for the reception of the dry cells, a partition within the box separating adjoining dry cells, said partition having 115 a slot in its upper end along the line of tangency of the dry cells on opposite sides of the partition, and means for engagement with the binding posts of the dry cells for restraining movement of the dry cells to prevent entry of the binding posts 120 into said slots. 125
